(57) **CLAIM**

I claim the ornamental design for a cat grooming arch, as shown and described.

DESCRIPTION

FIG. 1 is a perspective view of the cat grooming arch according to the present design;

FIG. 2 is a right side view of the present design, a corresponding left side view being a mirror image thereof;

FIG. 3 is a front view of the present design, a corresponding rear view being a mirror image thereof;

FIG. 4 is a top elevational view of the present design; and,

FIG. 5 is a bottom elevational view of the present design.

The broken line showing of the environment in FIGS. 1-5 is for illustrative purposes only and forms no part of the claimed design.
